(57) **CLAIM**

The ornamental design for packaging container, as shown and described.

DESCRIPTION

FIG. 1 is a perspective view of the invention.

FIG. 2 is a front view of the invention.

FIG. 3 is a rear view of the invention.

FIG. 4 is a top plan view of the invention.

FIG. 5 is a bottom plan view of the invention.

FIG. 6 is a right side view of the invention; and,

FIG. 7 is a left side view of the invention.

The broken lines in the figures illustrate the portions of the design that form no part of the claimed design.
